GESELLSCHAFT, OF ESSEN-ON-THE-RUHR, GERMANY.

MECHANICAL TIME-FUSE.

1,072,545.

Specification of Letters Patent.

Patented Sept. 9, 1913.

Application filed May 22, 1911. Serial No. 628,847.

To all whom it may concern:

Be it known that I, KARL WIESER, a subject of the Emperor of Germany, and a resident of Bredeney, Germany, have invented 5 certain new and useful Improvements in Mechanical Time-Fuses, of which the following is a specification.

The present invention relates to a mechanical time fuse, having a locking plate attached in such a manner by friction to a spindle, actuated by the driving gear, that the locking plate may be turned independently of the driving gear of the fuse, with the object of setting the fuse.

15 The invention consists in a device whereby the locking plate will be locked to the spindle, when actuated on by the inertia caused by the firing of the gun.

An embodiment of the invention is shown 20 in the drawing, wherein—

Figure 1 is a longitudinal section of the fuse, with some of the parts shown in full. The following figures are in larger scale, and Fig. 2 is a plan section on line 2—2 25 of Fig. 1, seen from above; and Fig. 3 is a section on line 3—3 of Fig. 2, looking in the direction of the arrow "x."

The function of the locking plate A, Fig. 1, is to prevent any swinging of the hook C that would set the firing spring B free, before the time has elapsed for which the fuse is set. This is accomplished, in well-known manner, by the locking plate A, with the assistance of a lever (not shown), compelling the hook C to hold the firing spring B cocked. The said locking plate, being made of a comparatively soft material, aluminum for instance, is mounted on a spindle D, Fig. 3, which is operated by the 30 driving gear of the time fuse, as for instance a clockwork, not shown in the drawing. During transportation of the fuse, the locking plate A is held on the spindle D simply by friction, so that the plate A may 35 be turned independently of the spindle D, for setting the fuse, actuated by the dome E through the coupling a¹ e¹.

The locking plate A is supported by a cup-spring F, Fig. 3, resting against a shoul-

der d¹ of the spindle D. A pressure block 50 G, having a soft metal filling g¹, is mounted on top of the locking plate A, in a manner best shown in Fig. 3. A collar nut d², screwed on to the threaded end d³ of the spindle D, holds the different parts together. 55 The threaded end d³ reaches up through the block G, where it is partly inclosed by the soft metal filling g¹. The amount of friction that is required to couple the locking plate A and the spindle D together, may be adjusted by turning the nut d² on the spindle, thus changing the pressure of the cup-spring F. The spindle D has between its shoulder d¹ and the threaded end d³ a square part d⁴ 60 tapering toward the threaded end d³, Fig. 3, so that it may enter partly into a suitably shaped opening in the locking plate A, when said plate is axially displaced from its position indicated in Fig. 3 against the pressure of the spring F. Until the fuse is used, the opening in said plate A lies altogether above the square part d⁴ of the spindle, so that the plate A, in setting the 65 fuse, may be turned without hindrance around the spindle D. The axial displacement of the locking plate A has furthermore the advantage, that it is possible to construct the coupling a¹ e¹ very simply, the said axial displacement of the locking plate 70 being utilized for automatically disconnecting said coupling. As is shown in Figs. 2 and 3, it is enough to solidly attach an arm a¹ to the locking plate A, and to the outer adjustable dome E likewise secure a fork e¹ 75 engaging said arm before the displacement takes place, but directly thereafter the coupling a¹ e¹ is disengaged. The simplicity of said coupling is evident, as, while according to the present invention both parts of the 80 coupling are rigidly attached to their respective carriers, in heretofore known time fuses, at least one of said coupling members had to be movably secured to its carrier.

On firing the projectile, the locking plate 95 A, together with the pressure block G, is snapped back against the spring pressure, according to the law of inertia, and forced

over the square d^4 , the edges thereof cutting into the locking plate, thus securing it to the spindle D. The soft metal filling g^1 will then be pressed into the threads of the 5 spindle, thereby preventing the spring F from pushing the locking plate back to its original position, on disappearance of the force of inertia. At the same moment that the locking plate A has thus been secured 10 to the square part d^4 , the arm a^1 has slipped out of the grip of the socket e^1 ; and the locking plate will begin to revolve with the spindle D, actuated by the driving gear of the time fuse, whereupon the hook C will 15 set free the firing spring B, directly the time has elapsed for which the fuse was set. As the locking plate A, at the moment of uncoupling from the dome E, is already securely attached to the spindle D, the tangentially acting forces of inertia, that comparatively late obtain their greatest power, 20 will be unable to turn the locking plate on the spindle D. Through this a source of failure, that must not be neglected, has been eliminated.

I claim:

1. In a mechanical time fuse comprising a fuse setting means, a spindle and a driving gear for said spindle; a member mounted on 30 said spindle, said member being adapted to turn independently of the spindle in setting the fuse and to be locked to the spindle by the shock from the firing of the projectile.
2. In a mechanical time fuse comprising a fuse setting dome, a driving spindle; a member in engagement with said dome during the setting of the fuse, said member being mounted on said spindle and adapted to 40 turn with the dome for setting the fuse, independently of the spindle; said member being brought into engagement with the spindle by the shock from the firing of the projectile; this shock causing the disconnection between said dome and said member, simultaneously with the interlocking of said member and said spindle.
3. In a mechanical time fuse comprising a fuse setting dome, a driving spindle; a 50 member in engagement with said dome during the setting of the fuse, said member mounted on said spindle and adapted to turn with the dome for setting the fuse independently of the spindle; said member being brought into engagement with said spindle by the shock from the firing of the projectile; this shock causing an axial displacement of said member, thereby disconnecting the member from said dome, simultaneously 55 with the interlocking of said member and said spindle.
4. In a mechanical time fuse comprising a fuse setting dome, a driving spindle; a locking plate mounted on said spindle and

adapted to turn independently thereof in 65 setting the fuse; a coupling between said plate and said dome comprising two parts engaging each other and firmly attached respectively to said plate and said dome; said locking plate actuated by the shock 70 from the firing of the projectile, receiving a limited axial movement, thereby severing its coupling with said dome and simultaneously interlocking firmly with the spindle, causing the plate to revolve with the spindle.

5. In a mechanical time fuse, having a fuse setting dome, a driving spindle; a locking plate mounted on said spindle and adapted to turn independently thereof in 80 setting the fuse; a coupling between said locking plate and said spindle comprising a flat part on the spindle under said locking plate, a pressure block mounted on said spindle over the locking plate, a core of soft material in said pressure block, a cup-spring mounted against a shoulder on said spindle, supporting said locking plate, and a nut threaded on the end of the spindle 85 for holding said cup-spring, locking plate, pressure block and core pressed against 90 said shoulder on the spindle; said locking plate and pressure block with core, actuated by the shock from the firing of the projectile, being axially displaced, thereby locking them firmly to the spindle, simultaneously severing the connection of said plate 95 and said dome.

6. In a mechanical time fuse having a fuse setting dome, a driving spindle; a locking plate, a dome coupling between said 100 plate and said dome, comprising an arm firmly attached to said plate and a fork firmly attached to said dome and in engagement with the arm, a spindle coupling between said locking plate and said spindle, 105 comprising a flat part and a shoulder on the spindle, a pressure block mounted on the spindle, a pliable core in said block, a spring mounted between said locking plate and said shoulder, a nut at the end of the spindle 110 adapted to hold the parts of said spindle coupling against the shoulder on the spindle; the shock from the firing of the projectile causing an axial displacement of said locking plate and block and the subsequent disengagement of said arm and said fork, releasing the dome coupling; together with the subsequent engagement of spindle and locking plate by the flat part of the spindle piercing the metal of the locking 115 plate and the cores closing up around the spindle, bringing the spindle coupling into engagement.

7. In a mechanical time fuse comprising a fuse setting means, a spindle and a driving 125 gear for said spindle; a member mounted on said spindle and adapted to turn independently thereof in setting the fuse, said spindle

having an abutment for said member; and a pressure block mounted in advance of said member and adapted to be rearwardly displaced by the action of inertia on firing, thereby driving said member against the abutment of said spindle and locking it thereto.

The foregoing specification signed at Barmen, Germany, this 9th day of May, 1911.
